UNITED STATES PATENT OFFICE.

CHARLES E. BENTLEY, OF NEW YORK, N. Y.

DESIGN FOR A PILLOW-TOP.

SPECIFICATION forming part of Design No. 35,602, dated January 21, 1902.

Application filed November 18, 1901. Serial No. 82,796. Term of patent 3½ years.

To all whom it may concern:

Be it known that I, CHARLES E. BENTLEY, a citizen of the United States of America, and a resident of the borough of Manhattan, city 5 of New York, State of New York, have invented and produced a new and original Design for a Pillow-Top, of which the following is a specification, reference being had to the accompanying drawing, forming part thereof, and which is a plan view of a pillow-top illustrating my design.

This design comprises a centerpiece or field representing a cluster of geranium blossoms 1 and leaves 2 and a foliated marginal portion having the outline of a series of leaf-like tabs 3, which radiate from the central cluster of geranium leaves and blossoms and taper outward at the edges toward their point or outer end.

A minor feature of the design comprises a 20 border or band 4, extending along the edge of each radial tab from its base to its point.

The more essential features of the design are the central representation of a cluster of geranium blossoms and leaves surrounded by 25 radiating and tapering leaf-like tabs forming a foliated margin to the geranium-leaf-and-blossom centerpiece.

I claim as my invention—

The design for a pillow-top, substantially 30 as herein shown and described.

CHARLES E. BENTLEY.
